UNITED STATES PATENT OFFICE

128,330

DESIGN FOR AN AIRPLANE

Harold W. Case, Dayton, Ohio

Application October 18, 1939, Serial No. 87,713

Term of patent 7 years

To all whom it may concern:

Be it known that I, Harold W. Case, a citizen of the United States residing at Dayton, in the county of Montgomery and State of Ohio, have invented a new, original, and ornamental Design for an Airplane, of which the following is a specification, reference being had to the accompanying drawings, forming part thereof.

The characteristic features of my design reside in the portions shown in full lines in the drawings.

I claim:

The ornamental design for an airplane, as shown and described.

HAROLD W. CASE.
